COVERING SPINDLE

Otto W. Schlums, Whitinsville, Mass., assignor to
 Whitin Machine Works, Whitinsville, Mass., a
 corporation of Massachusetts

Application July 22, 1940, Serial No. 346,770

4 Claims. (Cl. 57—18)

This invention relates to the manufacture of covered thread, and particularly to certain improvements in spindles adapted for use in thread-covering machines. In such machines, the thread to be covered is drawn upward through an axial passage in the covering spindle, and the covering yarn is supplied from a spool or yarn package mounted on the spindle and rotated about the axially disposed but non-rotated thread.

The covering is usually applied to a rubber thread which is dusted with talc to prevent adhesion. This talc is frequently gritty and is very penetrating, so that spindle bearings quickly load up with talc and the spindles drag and run below their scheduled speed. This produces irregular winding and decreased thread value, as uniform winding is a prime requisite of high-grade covered thread.

It is the general object of my invention to improve the construction of such covering spindles and particularly to prevent entrance of dust and dirt to the bearings thereof.

Other objects of my invention are to provide improved means for lubricating the flier used on such spindles, and to provide an improved guide for the thread to be covered.

My invention further relates to arrangements and combinations of parts which will be herein-after described and more particularly pointed out in the appended claims.

A preferred form of the invention is shown in the drawing, in which

Fig. 1 is a sectional side elevation of a covering spindle embodying my improvements;

Fig. 2 is a side view of a cap, looking in the direction of the arrow 2 in Fig. 1 and with the spring casing partially broken away;

Fig. 3 is a plan view of the cap;

Fig. 4 is a sectional side elevation, taken along the line 4—4 in Fig. 3;

Fig. 5 is a bottom view of the cap, looking in the direction of the arrow 5 in Fig. 4;

Fig. 6 is a plan view of the spring casing;

Fig. 7 is a side elevation of a thread guide holder;

Fig. 8 is a plan view thereof;

Fig. 9 is a side elevation of the thread guide; and

Fig. 10 is a sectional side elevation of a clamping nut.

Referring to the drawing, my improved covering spindle comprises a base 10 extending somewhat loosely through an opening 11 in a frame member 12. The base is yieldingly seated on said frame member by a heavy coil spring 14 engaging

a washer 15 and compressed by a clamping nut 16. A center post 20 is mounted in the base 10 and is secured therein by a thread guide holder 22 (Figs. 1, 7 and 8) having a split threaded portion 23 and a split tapered portion 24. A thread guide 25, preferably in the form of a porcelain bushing, is mounted in the lower end of the holder 22 and is a press fit therein (or may be cemented therein if so preferred).

The holder 22 is slipped over the projecting lower end of the center post 20 and is securely clamped thereon by tightening a nut 27 on the portions 23 and 24 of the holder. The inside of the nut has a tapered bearing portion 28 co-acting with the tapered portion 24 to compress the holder and grip the lower end of the center post 20.

The thread guide 25 has a bell-mouthed center opening 29 and substantially reduces friction on the thread T as the thread is drawn upward through an axial opening 30 in the center post 20.

An idle pulley or whirl 32 is mounted to rotate on an inner ball race 33 which extends into a recess 34 in the base 10 and which is secured therein by one or more clamping screws 35. The race 33 fits somewhat loosely in the recess 34, so that tightening of the screw or screws 35 forces the race 33 against the post 20 and thus serves also to hold the post 20 from rotation.

All of the parts thus far described, with the exception of the idle whirl 32, are normally non-rotatable.

A bearing support 40 is clamped to the center post 20 by binding screws 41 and non-rotatably supports the outer races 42 and 43 of upper and lower ball bearings in the covering spindle. The inner race 44 of the upper bearing is mounted on a tapered tube 45, free from the center post 20 but rotatable about the axis thereof. A barrel 46 for the yarn package P is firmly seated on the tapered tube 45 and rotates therewith.

The inner race 48 of the lower ball bearing is fixed on a sleeve 49 extending upward from a driving whirl 50 which has an enlarged flange 51 fixed in a recess in the lower end of the barrel 46 and rotatable therewith.

A sealing element 55 is provided below the balls 56 of the upper bearing and above the balls 57 of the lower bearing. It is accordingly impossible for any dust or talc, which might find its way downward between the rotated tube 45 and the center post 20 or upward between the sleeve 49 and the post 20, to enter either of the ball bearings on which the barrel 46 and the yarn package P rotate. Furthermore, no dust or talc can enter

through the press-fit bearing of the barrel 46 on the tube 45 or between the flange 51 and the enlarged lower end of the barrel 46.

Accordingly, the ball bearings are securely sealed from entrance of dirt or talc from either direction and will operate satisfactorily for long periods of time without becoming clogged or dragging at irregular speed.

The yarn package P commonly includes a paste-board tube 60 on which the yarn is wound and which is a sliding fit on the barrel 46. A plurality of spring-pressed balls 61 may be provided in the barrel to supply additional driving contact with the sleeve 60.

A traveler 63 is loosely mounted on the upper end of the tapered tube 45 and is provided with a yarn guide 64 through which the yarn Y is guided as it is drawn upward for winding on the thread T.

A cap 70 is firmly mounted on the slightly tapered upper end 71 of the center post 20 and is held from rotation thereby. As the yarn Y rotates with the yarn package P, centrifugal force will move the traveler 63 outward or to the left in Fig. 1. As the outer surface of the tube 45 is tapered, the traveler tends to move upward against the lower face of the cap 70 and is suitably retarded by friction thereon.

The details of construction of the traveler and its coaction with the tapered tube form the subject matter of my copending application Serial No. 346,769, filed July 22, 1940.

Special provision is made herein for lightly lubricating the traveler 63 and such provision is shown in detail in Figs. 2 to 6.

An annular recess 74 is formed in the periphery of the cap 70 and is surrounded by a second annular recess 75 which is wider but of less depth. Six downwardly inclined radial openings 77 connect the annular recess 74 with an enlarged cylindrical bottom opening 78 which loosely receives the upper end of the tapered tube 45.

A wicking W is wound in the recess 74 and is threaded in and out of the radial passages 77 to provide three chord-like portions 80 which loosely contact the exterior of the rotating tapered tube 45.

A spring casing 82 is seated in the outer annular recess 75 and the ends of the casing 82 closely abut when in operative position, thus forming a substantially continuous outer casing for the recess 74 which constitutes in effect an oil reservoir. Oil may be supplied through an upwardly extended recess 85.

The oil thus supplied gradually travels along the wicking by capillary action until it reaches the chord-like portions 80, where it is transferred to the rotating tube 45 and serves to lubricate the traveler 63, which has a comparatively slow turning movement relative to the tube 45.

The method of operation is readily understood

from the preceding description. A driving belt B runs on the loose pulley or whirl 32 when the spindle is at rest and is shifted to the driving whirl 50 for a covering operation.

5 The package P is then rotated at substantial speed on the upper and lower ball bearings, and at the same time the thread T is drawn upward through the central passage 30 in the post 20.

The drag of the traveler 63 and the upward pull of the thread T causes the yarn Y to be wound uniformly on the outer surface of the thread. The frictional resistance of the traveler 23 may be varied by changing the weight of the traveler or removing some portion of stock therefrom.

10 In actual thread-covering operations, two spindles such as are herein described are commonly superposed and rotated in opposite direction. The thread T is drawn successively through the two spindles, thus receiving two covering layers of opposite wind.

15 Having thus described my invention and the advantages thereof, I do not wish to be limited to the details herein disclosed, otherwise than as set forth in the claims, but what I claim is:

20 1. In a covering spindle, a fixed center post, a yarn-supporting barrel rotatable about the axis of said post, a driving whirl fixed to said barrel, upper and lower ball bearings having inner races fixed to said barrel and whirl respectively, and a supporting member for the outer races of said bearings which is fixed to said center post.

25 2. In a covering spindle, a fixed center post, a yarn-supporting barrel rotatable about the axis of said post, a driving whirl fixed to said barrel, upper and lower ball bearings having inner races fixed to said barrel and whirl respectively, and a supporting member fixed to said center post and interposed between said bearings and providing a fixed support for the outer races of said ball bearings.

30 3. In a covering spindle, a fixed center post, a yarn-supporting barrel rotatable about the axis of said post, a driving whirl fixed to said barrel, upper and lower ball bearings having inner races fixed to said barrel and whirl respectively, a supporting member for the outer races of said bearings which is fixed to said center post, and means to seal said bearings at the sides thereof adjacent said fixed supporting member.

35 4. In the combination in a covering spindle as set forth in claim 1, a fixed base for said center post having a recessed upper end, an idle whirl positioned below said driving whirl and forming the outer race of a ball bearing, an inner race for said ball bearing axially extended into the recess in said base member, and a single means to clamp both said inner race and said center post in said fixed base.
